ATTORNEY

UNITED STATES PATENT OFFICE

LEON PIERCE, OF NEW YORK, N. Y.

EARTH-PENETRATOR FILE

Application filed September 21, 1927. Serial No. 220,882.

The main object of this invention is to provide means for sinking shells into the soil in which concrete is poured later. The main difficulty encountered in providing openings in the soil to an appreciable depth sometimes amounting to thirty feet, is that the shell which bounds the opening formed by the sinking member oftentimes collapses owing to its delicate structure as they are ordinarily 5 common cylindrical sleeves arranged end to end and connected with a lap joint. The sleeve illustrated by this invention is reinforced to strengthen its structure so as to enable it to retain its shape throughout the 10 operation of sinking the shell and providing the hole in which the shell fits simultaneously.

Another object of this invention is to provide a conical sinking element which penetrates the soil and forms the hole, and has mounted thereon the sleeve sections into 20 which the concrete is to be poured. This penetrator element is constructed with a view to eliminating the greatest amount of friction which exists between the shell and the surface of the penetrator so that the latter may be conveniently extracted for the after 25 operation of pouring the cement without disarranging these shells.

Still another object of this invention is to provide a penetrator which permits the use of a drop or steam hammer within the penetrator which is capable of sinking the latter or extracting it accordingly as the throw of 30 the hammer is adjusted.

The above and other objects will become apparent in the description below, in which characters of reference refer to like-named parts in the drawings.

Referring briefly to the drawing:

Figure 1 is a longitudinal sectional elevational view of the preferred form of penetrator with the shell mounted in place thereon and a drop hammer within its confines.

Figure 2 is an exterior side elevational

view of Figure 1 with a portion of the shell removed therefrom.

Figure 3 is a side elevational view of the penetrator.

Figure 4 is a top plan view of Figure 1.

Figure 5 is a cross sectional view through the penetrator, taken on line 5—5 of Figure 4.

Referring in detail to the drawing, the numeral 35 indicates a conical structure which forms the body of the penetrator. This 55 penetrator has a hemi-spheroid nose 11 at its lower closed end which first penetrates the soil through which it is to be forced and the upper end is open. The penetrator is of the simplest form and is provided with lugs 12 60 at spaced-apart positions thereon.

A hollow bore 25 extends downwardly into the penetrator from its open end. This bore 25 is preferably cylindrical in shape and receives a drop hammer such as indicated by 65 the numeral 26, which is suspended from a cable 27 and is reciprocal in this bore. At the upper end of the penetrator a pair of diametrically opposite lugs 28 and 29 are formed. These lugs extend inwardly and 70 are adapted to retain a header plate 30, which has two recesses 31 and 32, in place. The recesses 31 and 32 are of a dimension sufficient to permit the passage of the lugs therethrough as the header plate 30 is slipped 75 over the open end of the penetrator. The greater length of the external conical surface of the penetrator is corrugated by forming ridges 33 thereon which are interspersed by canals 34. The bore 25 is adapted to receive either a drop hammer, as shown in the figure or a steam hammer, either one of which 80 may be so constructed that the penetrator may be forced upward or into the soil if desired in the use of the device. These ridges 85 and canals are formed on the external surface of the penetrator so that the greater amount of friction is eliminated between the penetrator and the shell sections which it is adapted to carry. These shells are formed of coupled 90

sections, such as indicated by the numerals 36, 37 and 38. The lowermost section, which encloses the tip of the penetrator, is more solidly built and more substantial than any 5 of the other sections and has a hemi-spherical nose 39 and is termed the shoe. The remaining and successive sections are telescoped partly into each other, as indicated in Figure 1, and all of these sections are provided with 10 encircling grooves 40 at spaced-apart positions along their entire length.

It is the purpose of this invention to provide a means of sinking a tapering shaft in the soil lining this shaft with sleeves and 15 filling the resultant space after the penetrator has been extracted with cement for the purpose of piling. The ordinary skin or shell which is slipped over a penetrator element and is of annular construction causes an excessive amount of friction which occurs between the contacting surfaces of the sleeves 20 and the surface of the penetrator when the penetrator is removed from the shaft, and owing to this friction one or more sections 25 of shell adhere to the penetrator and carried with it. This danger is completely eliminated by providing a free space between the shell and the penetrator except at various 30 positions where the shell remains in slight contact with the penetrator. This is accomplished by inwardly bending in semi-circular curves, portions of the material forming thereby grooves 40 which encircle the shell 35 sections as indicated. To further eliminate friction, the external surface of the penetrator has longitudinal ridges and canals 33 and 34 respectively formed thereon. These ridges and canals extend the greater length 40 of the penetrator and lessen the contact thereby had between the shells and the penetrator to a greater extent. The header plate 30 closes the top of the bore in the penetrator and has an opening formed axially therein through which a cable, such as 27, may be inserted. 45 The cable is for the purpose of lifting a steam hammer when the latter is to be used or for the purpose of suspending a drop hammer when that type is to be used. This header plate is located in position in the 50 penetrator below the lugs 28 by passing the recesses in the header plate downwardly past the lugs 28 and then rotating the header plate a distance of 90°. After being secured in this manner the header plate locks 55 a steam or drop hammer in the bore 25 of the penetrator and also serves as an anvil for the drop hammer or steam hammer when the penetrator is to be extracted from the shaft it has formed.

60 It is to be noted that certain changes in form and construction may be made without departing from the spirit and scope of the invention.

I claim:

65 1. A device for forming a pile shaft com-

prising a cone-shaped penetrator having a hemi-spherical nose and a corrugated surface extending upwardly from a point above said nose, said penetrator having a cylindrical bore extending axially therein, a drop hammer reciprocal in said bore, a header plate having diametrically opposed recesses therein, means on said recesses for securing said header plate in position on said penetrator, and sleeve sections slipped over said penetrator adapted to be permanently sunk into a shaft formed by said penetrator.

2. A device for forming a pile shaft comprising a cone-shaped penetrator having a hemi-spherical nose and a corrugated surface 70 extending upwardly from a point above said nose, said penetrator having a bore extending axially therein, a drop hammer in said bore, a header plate having diametrically opposed recesses therein, diametrically opposed lugs on said penetrator above said bore, said lugs engaging the upper surface of said header plate when the latter has been rotated, said header plate retaining said drop hammer in said bore, so that the recesses therein are 75 disaligned with the lugs for securing the header plate in position over the bore, the drop hammer being adapted to contact with either the bottom of the bore or the header plate for extracting or urging downwardly the penetrator, and sleeve sections adapted to be slipped over said penetrator.

3. A device for forming a pile shaft comprising a cone-shaped penetrator having a hemi-spherical nose and a corrugated surface 80 extending upwardly from a point above said nose, said penetrator having a bore extending axially therein, a drop hammer in said bore, a header plate having diametrically opposed recesses therein, diametrically opposed lugs on said penetrator above said bore, said lugs engaging the upper surface of said header plate when the latter has been rotated, so 85 that the recesses therein are disaligned with the lugs for securing the header plate in position over the bore, the drop hammer being adapted to contact with either the bottom of the bore or the header plate for extracting or urging downwardly the penetrator, said header plate serving as an anvil on the upstroke of said drop hammer, tapering sleeve sections slipped over said penetrator and connected end to end by means of a slip joint.

4. A device for forming a pile shaft comprising a cone-shaped penetrator having a hemi-spherical nose and a corrugated surface 90 extending upwardly from a point above said nose, said penetrator having a bore extending axially therein, the bore being adapted to receive a drop hammer, a header plate having diametrically opposed recesses therein, diametrically opposed lugs on said penetrator above said bore, said lugs engaging the upper surface of said header plate when the latter has been rotated, so that the recesses 95

therein are disaligned with the lugs for securing the header plate in position over the bore, a drop hammer being adapted to contact with either the bottom of the bore or the header plate for extracting or urging downwardly the penetrator, tapering sleeve sections slipping over said penetrator and connected end to end by means of a slip joint, said sleeve sections being of larger diameter than the diameter of the penetrator, and spaced-apart annular encircling grooves on said sleeve sections, the base of said grooves seating upon the corrugated surface of said penetrator when said shells are being sunk into a shaft.

In testimony whereof, I affix my signature.
LEON PIERCE.
